UNITED STATES PATENT OFFICE.

JOHN FRANCIS O'MALLEY, OF MOUNT VERNON, NEW YORK.

MACHINE-GUN.

1,366,210.

Specification of Letters Patent. Patented Jan. 18, 1921.

Application filed January 14, 1920. Serial No. 351,320.

To all whom it may concern:

Be it known that I, JOHN FRANCIS O'MALLEY, a subject of the King of Great Britain, and a resident of Mount Vernon, in the 5 county of Westchester and State of New York, have invented a new and Improved Machine-Gun, of which the following is a full, clear, and exact description.

The invention relates to machine guns 10 such as shown and described in the Letters Patent of the United States, No. 1,307,316, granted to me on June 7, 1919, and in the application for Letters Patent of the United States, Serial No. 266,194, filed by me on 15 December 11, 1918.

The object of the present invention is to provide a new and improved machine gun of the type above referred to and arranged to supply the cartridges to the barrel in use 20 at the time from an intermittently revolving magazine wheel instead of from a cartridge belt.

Another object is to permit of quickly and conveniently replacing an empty magazine 25 wheel by a filled one.

With these and other objects in view, the invention consists of certain novel features of construction as hereinafter shown and described and then specifically pointed out 30 in the claims.

A practical embodiment of the invention is represented in the accompanying drawings forming a part of this specification, in which similar characters of reference indicate corresponding parts in all the views.

Figure 1 is a side elevation of the improved machine gun;

Fig. 2 is a plan view of the same;

Fig. 3 is an enlarged sectional side elevation of the same;

Fig. 4 is a cross section of the same on the line 4—4 of Fig. 3;

Fig. 5 is a perspective view of the firing pin and the means for actuating the same;

Fig. 6 is a plan view of the body of the magazine wheel with the cover ring removed;

Fig. 7 is a plan view of the cover ring; and

Fig. 8 is a sectional perspective view of a portion of the magazine cartridge wheel.

The gun body or main frame 10 of the machine gun is preferably made in two parts 11 and 12 fastened together by transverse 55 screws 13, and the said parts 11 and 12 are provided with transversely extending inter-

locking tongues and grooves, one fitting into the other, to securely hold the parts against longitudinal movement one on the other, as will be readily understood by reference to Fig. 2. The forward end of the part 12 of the gun body 10 is provided with a pivot 14 on which are mounted reversible barrels 15 and 16 of the type more fully shown and described in the Letters Patent and the application above referred to, so that further description of the same is not deemed necessary, it being sufficient to state that the barrel in uppermost position at the time is the one through which the bullets are fired. 65 Each of the barrels 15 and 16 is provided with a bore 17, of which the bore of the uppermost barrel is successively in register with cartridge seats 20 formed in a cartridge magazine wheel 21 secured on the upper end 70 of a shaft 22 journaled in suitable bearings arranged on the part 12 of the gun body 10. The lower end of the shaft 22 is provided with a bevel gear wheel 25 in mesh with a bevel gear wheel 26 secured on the 75 forward end of a longitudinally extending shaft 27 journaled in the gun body 10, as plainly indicated in Fig. 3. The rear end of the shaft 27 passes out of the gun body 10 and along the under side thereof, and on 80 this rear end is secured a bevel gear wheel 30 in mesh with a bevel gear wheel 31 secured on a transversely extending shaft 32 journaled in suitable bearings 33 attached to the under side of the gun body 10, as 85 plainly shown in Figs. 1 and 3. A crank arm 34 is attached to the right-hand side of the shaft 32 to permit the user of the gun to conveniently turn the shaft 32 with a view to rotate the shaft 27 which by the 90 gear wheels 26, 25 rotates the shaft 22 and consequently the magazine cartridge wheel 21 to move the cartridge seats 20 successively in register with the bore 17 of the barrel 15 or 16 in uppermost position at the time. 100 The cartridge seats 20 are disposed radially and each is adapted to support a cartridge 40 with the bullet 41 extending outwardly within close proximity to the peripheral face of the magazine wheel 21, as 105 plainly indicated in Fig. 3. Each of the seats 20 of the magazine wheel 21 is formed partly on the top of an annular flange 42 projecting from the hub 43 of the wheel and partly in the under side of a detachable 110 covering ring 44 removably fastened by suitable spring catches 45 to the hub 43, as

plainly indicated in Fig. 4. The hub 43 of the magazine wheel 21 is provided at the under side with a recess 46 and the side wall 47 of this recess 46 is provided with vertical slots 48 each of a width corresponding approximately to the diameter of a cartridge adjacent the cartridge rim 49 so that the latter abuts against the inner face of the wall 47. The top of each slot 48 is at the top of the hub 43 and the inner portion of the slot at the top is enlarged sidewise for the passage of the rim 49 of the cartridge. By the arrangement described the magazine wheel is loaded with the cartridges by dropping the same with the rim ends down the slots 48. The covering ring 44 is provided along its inner wall with vertical ribs 50 which fit into the slots 48 and rest at their bottoms on top of the cartridges 20 in front of the rims 49 to securely hold the cartridges in place during firing. The hub 43 is removably held on the upper end of the shaft 22 by a nut 55 screwing on the threaded reduced top portion 56 of the said shaft 22 to permit of conveniently removing an empty cartridge wheel from the shaft 22 and replacing it by a filled one. It is understood that when a cartridge wheel is removed, the covering ring 44 can be readily removed from the hub 43 on retracting the catches 45 and lifting the ring off the flange 42. The empty shells of the cartridges 40 can now be dumped out. The seat portions of the flange 42 can now be readily filled with cartridges 40, after which the covering ring 44 is replaced and locked in position by the catches 45. By reference to Figs. 1 and 3 it will be noticed that the gun body 10 is provided at the top with a cut-out portion 58 to make the top of the horizontally disposed cartridge magazine wheel 21 flush with the top of the gun body 10 with a view to permit proper sighting of the gun.

In order to fire the cartridges 40 as they successively move into operative position relative to the bore 17 use is made of a firing pin 60 mounted on a slide 61 mounted to reciprocate longitudinally in a suitable bearing 62 formed in the gun body 10, as plainly shown in Fig. 4. The slide 61 is provided with a slot 63 through which extends the shaft 22, and the said slide 61 is pressed in a forward direction by a spring 64 coiled on a rod 65 mounted to slide in a bore 66 formed in the gun body 10 (see Fig. 3). The top of the slide 61 is provided with a V-shaped tooth 70 engaging a toothed wheel 71 secured to the shaft 22 so that when the latter is rotated a longitudinal reciprocating motion is given to the slide 61 to cause the firing pin 60 to strike the rim 49 of the cartridge 40 in register at the time with the bore 17 of the gun barrel 15 or 16 in uppermost position at the time. It is understood that motion to the left is imparted to the

slide 61 by the teeth of the toothed wheel 71 acting on the tooth 70, and return or firing movement is given to the slide 61 by the action of the spring 64.

In using the gun, the operator turns the crank arm 34 thus causing the magazine wheel 21 to rotate continually. At the same time the firing pin 60 is actuated to fire the cartridges 40 successively and at the time they are in register with the bore 17.

The forward end of the gun body 10 is mounted on a suitable support 80, preferably of the construction shown and described in the application for Letters Patent above referred to, so that further description of the same is not deemed necessary.

The gun body 10 and the barrels 15 and 16 are provided with suitable rear and front sights 90 and 91, of any approved construction.

Having thus described my invention, I claim as new and desire to secure by Letters Patent:—

1. In a machine gun, a gun body provided with a barrel, a horizontally disposed cartridge magazine wheel provided with radially disposed cartridge seats adapted to register successively with the said barrel, each seat being adapted to hold a single cartridge with the bullet thereof at the outer end, a vertically disposed shaft journaled in the said gun body and on which the said magazine wheel is secured to rotate with the shaft, means for driving the said shaft, a spring-pressed firing pin mounted to slide in the said gun body and adapted to fire the cartridge in register at the time with the said barrel, and means connected with the said shaft imparting a reciprocating motion to the said firing pin.

2. In a machine gun, a gun body provided with a barrel, a horizontally disposed cartridge magazine wheel provided with radially disposed cartridge seats adapted to register successively with the said barrel, each seat being adapted to hold a single cartridge with the bullet thereof at the outer end, a vertically disposed shaft journaled in the said gun body and on which the said magazine wheel is secured to rotate with the shaft, means for driving the said shaft, a spring-pressed firing pin mounted to slide in the said gun body and adapted to fire the cartridge in register at the time with the said barrel, a tooth on the said firing pin, and a toothed wheel on the said shaft engaged by the said tooth to reciprocate the firing pin.

3. In a machine gun, a revoluble cartridge magazine wheel provided with a body having a hub and an annular flange projecting integrally from the rim of the hub the latter having a central recess, a ring removably fitting on the said hub and overlying the said flange, cartridge seats formed partly in the said flange and partly in the said ring and

opening at their inner ends into the said central recess, the cartridge seats being disposed radially, the inner top portion of each cartridge seat being enlarged sidewise for the passage of the rim of a cartridge, the enlarged seat portion opening into the said recess, and locking means locking the said ring in place on the hub.

4. In a machine gun, a gun body provided with a barrel, a horizontally disposed magazine cartridge wheel provided with radially disposed cartridge seats in which cartridges are singly seated with the bullets outward and the rims inward, a vertical shaft journaled in the said gun body and on which the

said cartridge wheel is removably secured, a slide mounted to slide forward and backward in the said gun body, a firing pin attached to the said slide and adapted to successively fire the cartridges held in the rotating wheel and at a time a cartridge is in register with the barrel, actuating means connecting the said shaft with the said slide to move the latter in one direction, a spring pressing the said slide to move the latter in an opposite direction, and manually controlled means connected with the said shaft to rotate the latter.

JOHN FRANCIS O'MALLEY.
